EYELET SETTING TOOL AND CONTROL
MECHANISM THEREFOR

Julius A. Welebny, Rockville Centre, N. Y.

Application March 23, 1948, Serial No. 16,524

15 Claims. (Cl. 218—14)

1

The present invention relates to tools for setting eyelets or grommets and the like, and more particularly to such tools in cooperative association with mechanism for controlling the operation thereof.

The invention aims to provide a tool of the aforementioned character comprising elements which are in the nature of attachments adapted to be associated with conventional machines, such as drill presses or the like, to thereby convert such machines into machines adapted to accomplish special purposes.

Accordingly, an object of the present invention is to provide a tool of the aforementioned character which is relatively simple and inexpensive in construction, and is reliable in operation.

Another object is to provide a tool of the aforementioned character which is constructed and arranged for attachment to a great variety of conventional machines of different sizes and design.

Another object is to provide such a tool which converts conventional machines into automatic eyelet setting machines.

Another object is to provide a tool for more effectively setting eyelets and the like.

A further object consists in the combination and arrangement of elements whereby the foregoing objects may be accomplished.

Other and further objects will be obvious upon an understanding of the illustrative embodiment about to be described, or will be indicated in the appended claims, and various advantages not referred to herein will occur to one skilled in the art upon employment of the invention in practice.

In accordance with the invention, the foregoing objects are accomplished by providing a tool adapted to be carried by the spindle of a drill press or the like for effecting the spinning of eyelets or the like while applying vibration to the material into which the eyelet is being set, as well as to the eyelet, to facilitate forming the eyelet, and cooperating elements adapted to be carried by the column or other supporting structure of the drill press for automatically rendering the tool effective and ineffective during its movement on the spindle with respect to the work.

A preferred embodiment of the invention has been chosen for purposes of illustration and description and is shown in the accompanying drawing, forming a part of the specification, wherein:

Figure 1 is an elevational view of a portion of a drill press having a tool and control mechanism attached thereto.

Figure 2 is a sectional view taken along the line 2—2 on Figure 1.

Figure 3 is a view of the eyelet setting tool shown partly in elevation and partly in section.

2

Figure 4 is a longitudinal sectional view of the tool shown in Figure 3.

Figure 5 is a sectional view taken along line 5—5 on Figure 4.

Figure 6 is an exploded perspective view illustrating elements of the tool in detail.

Figure 7 is an elevational view partly in section taken along the line 7—7 on Figure 2.

Figure 8 is a sectional view taken along the line 8—8 on Figure 2, illustrating details of the control mechanism.

Figure 9 is a sectional view taken along the line 9—9 on Figure 8.

Referring to the drawings and more particularly to Figures 1 and 2 thereof, there is shown a portion of a drill press or similar machine having an upright column or structural member 10 and a rotatable spindle 11 supported on the column by a horizontal arm or bracket 12. The driving mechanism and the means for raising and lowering the spindle are not shown since such devices are well known. Furthermore it will be readily appreciated that such devices are adapted to be controlled manually or by automatic or semi-automatic means.

The drill press shown is equipped with apparatus in accordance with the present invention which generally comprises a tool 14 carried by the spindle 11 for setting a rivet or an eyelet E with relation to a work piece W supported by an anvil A, and control mechanism for the tool 14, including means generally indicated by the reference character 15 (Figure 2) supported on a two-piece bracket 16 of adjustable length, which is secured to the column 10, and including means generally indicated by the reference character 17 (Figure 1) carried by the spindle 11 for operating the means 15 during upward and downward movement of the spindle.

The eyelet setting tool 14 is illustrated in detail in Figures 3 to 6, and, as shown, comprises a spindle portion 20 threadedly or otherwise secured to the drill press spindle 11 at 21 (Figure 4) for rotation therewith, and a tubular sleeve or casing 22 coupled to the spindle portion 20 by a ring 24 to provide for relative rotation and axial movement between the casing 22 and the spindle portion 20.

The casing 22 is formed with a reduced lower portion 25 providing an upwardly facing shoulder 26, and is formed with a constricted tubular lower end 27 for engaging the work piece W and for holding it against the anvil A, the lower end having a bore 28 extending therethrough. The casing is further provided with a longitudinally extending vertical slot or recess 30 formed in the side wall thereof above the portion 25, and a lateral projection 31 at the upper end thereof, constituting a portion of a flange 32 (Figure 5),

the function of which will become apparent hereinafter.

The spindle portion 20 extends partly into the casing 22 and has a reduced tubular portion 34 at its lower end for providing a downwardly facing shoulder 35 and has a central bore 36.

An eyelet setting member in the form of a rod 37 formed with a spinning means 39 of conventional construction at the lower end thereof has its upper end extending into the bore 36 and is secured to the spindle portion by a set screw 40 or the like.

Relative rapid vibration between the rod 37 secured to the spindle portion 20 and the casing 22 is adapted to be effected by cam means which comprise a cam element on the shoulder 35, herein shown (Figure 6) as an annular member 41 having a pair of diametrically opposite radially extending grooves 42 on the underside thereof, a central aperture 44 through which the portion 34 extends, and a vertical off-center aperture 45 housing a pin 46 (Figure 4) secured to the spindle portion for preventing relative rotation between the latter and the annular member; and a second annular member 47 facing the member 41 having diametrically opposite radially extending ribs 49, a central aperture 50 through which the portion 34 extends, and a lateral projection or finger 51 keyed in the slot 30 to prevent relative rotation between the member 47 and the casing 22 but permitting relative axial movement thereof effected by the cooperation of the grooves 42 and ribs 49. The annular member 47 is urged into engagement with the annular member 41 by a spring 52 having its lower end supported on the shoulder 26 of the casing and having its upper end engaging the underside of the member 47 (Figure 4).

The control mechanism 15 for the tool 14 is best illustrated in Figures 1, 2, 7, 8 and 9, and comprises a movable member, such as an L-shaped member 55, pivotally mounted on the bracket 16 adjacent the free end thereof by a pin 56, and a latch element 57 pivotally mounted adjacent the member 55 by a pin 59.

The member 55 has a hook-shaped locking projection or finger 60 at one end thereof adapted to engage the stop projection 31 of the tool casing 22 and has an arm 61 at its other end formed with a cam face 63 at one side and latching means 62 adapted to cooperate with the latching element 57 as described hereinafter.

The latching element 57 has an arm 64 at one end thereof formed with latching means 65 adapted to cooperate with the latching means 62 of the member 55 and has an operating arm 66 at the other end thereof extending over a slot 67 in the bracket 16 and being formed with a cam face 69 at one side thereof (Figures 8 and 9), the purpose of which will become apparent hereinafter.

A spring 70 or the like has one end thereof connected to the arm 61 and has the other end thereof connected to the arm 64 for normally urging the member 55 into a position for effecting engagement of the stop projection 31 by the locking projection 60, and for normally urging the member 55 and the element 57 into a position for effecting latching cooperation of the means 62 and 65.

The control operating means 17 comprise a depending member 75 connected at its upper end for adjustment in a vertical direction by a clamp 76 or the like carried by the spindle sleeve 77 of the drill press, by way of example, and having a pair of bifurcated vertical fingers 79 and 80 at its

lower end for controlling the position of the member 55, as about to be described.

The finger 79 has a diagonal cam face 81 at its lower end for engaging the cam face 69 of the latching element to operate the latter to release the member 55; and the finger 80 has an enlargement 82 at its lower end formed with a cam face 84 at one side for engaging the cam face 63 to effect resetting of the member 55.

In operation, the bracket 16 and the member 15 are adjusted so that the cooperating parts thereof are properly positioned in working relation. The work piece W and the rivet or eyelet E extending therethrough are positioned on the anvil in axial alignment with the lower end 27 of the tool casing and the rod 37 adapted to extend therethrough.

Assuming that the drill press spindle 11 and the tool 14 carried thereby are in an upper position, 20 the member 15 is in the position with relation to the control means on the bracket 16, as shown in Figure 8, and the control means are positioned as shown in Figure 9 with the member 55 and the element 57 and their latching means 62 and 25 65 cooperating with the aid of the spring 70 to latch the member 55 in a position so that the projections 31 and 60 will not engage. With the parts so positioned, rotation of the drill press 30 spindle in a clock-wise direction, as viewed in Figures 2 and 9, will cause the tool casing 22 to rotate therewith without effecting vibration of the casing 22.

As the spindle 11 and the member 15 descend, the enlargement 82 on the finger 80 passes 35 through the slot 67 in the bracket and between the arms 61 and 66 without disturbing their positions (Figure 8). Upon further descent of the member 15, the cam face 81 on the finger 79 engages the cam face 69 on the arm 66 of the 40 latching element and effects clock-wise movement of the latter from the position shown in Figure 9 to the position shown in Figure 2. Such movement causes the latching means 62 and 45 65 to disengage, whereby the spring 70 urges the member 55 to the position shown in Figure 2 to enable the projection 60 thereon to engage the stop projection 31 on the tool casing 22 as the latter is rotated clockwise.

When the tool casing 22 is locked against 50 rotation, as just described, the spindle portion 20 rotates with respect to the casing 22 and the annular member 41, carried by the spindle portion, rotates with respect to the annular member 47, which is retained against rotation by the tool casing 22, whereby the grooves 42 and ribs 55 49 are rapidly moved into and out of registry under influence of the spring 52, the vertical movements of member 47 being transmitted through this spring to effect periodic vertical reciprocating movement or vibration of the tool casing 22.

As the tool moves into engagement with the work piece W, the work piece is vibrated by the end 27 of the tool casing 22 and the spinning means 39 sets the rivet or eyelet E. This vibration enables the eyelet and the work piece to be pulled tightly together before the completion of the spinning of the eyelet, whereby the eyelet may be securely attached to the work piece. 65

70 It will thus be seen that the lower end 27 of the casing 22 not only holds the work piece W in place but also imparts a vibratory, and hence, compressive force, like a trip hammer, against the work piece W.

75 Upon completion of the foregoing described

operation, the drill press spindle and tool are raised from their lowermost position, as shown in Figures 1 and 2. During the ascent thereof, the cam face 84 on the finger 89 engages the cam face 63 on the arm 61 to rock the member 55 in a counter-clockwise direction and to momentarily retain the member 55 in a position, such as shown in Figure 9, to enable the latching means 62 and 65 to reengage under the influence of the spring 70, whereby the control means member 55 and element 57 are relatched for the next operation.

From the foregoing description, it will be seen that the present invention provides an improved tool and operating mechanism for setting eyelets, rivets, tubular rivets, and the like, which tool and mechanism are simple and economical in construction and effective in operation. The apparatus in accordance with the present invention is readily adjustable and is adaptable for use in conjunction with a large variety of machines, such as drill presses and the like. The apparatus is rugged in construction and can readily withstand such rough usage to which it may normally be subjected.

As various changes may be made in the form, construction and arrangement of the parts herein, without departing from the spirit and scope of the invention and without sacrificing any of its advantages, it is to be understood that all matters herein are to be interpreted as illustrative and not in any limiting sense.

I claim:

1. In combination with a drill press or the like having a supporting column and a rotatable spindle, an eyelet setting tool carried by the spindle, said tool having relatively movable parts, one of said parts being rigidly secured to said spindle and adapted to rotate therewith, a bracket on the column having a free end extending towards the spindle, pivotal means on said bracket free end constructed and arranged to be positioned for arresting rotation of the other of said parts to lock the same to condition said parts for relative movement therebetween, means for locking said pivotal means in a position to prevent the same from arresting said other of said parts, and means associated with the spindle having an element for releasing said locking means upon movement of said element towards said bracket.

2. In combination with a drill press or the like having a supporting column and a rotatable spindle, an eyelet setting tool carried by the spindle, said tool having relatively movable parts, one of said parts being rigidly secured to said spindle and adapted to rotate therewith, a bracket on the column having a free end extending towards the spindle, pivotal means on said bracket free end constructed and arranged to be positioned for arresting rotation of the other of said parts to lock the same to condition said parts for relative movement therebetween, means for locking said pivotal means in a position to prevent the same from arresting said other of said parts, and means associated with the spindle having an element for releasing said locking means upon movement of said element towards said bracket, and having an element for permitting said locking means to be moved into latching position upon movement of said last mentioned element away from said bracket.

3. In combination with a drill press or the like having a supporting column and a rotatable spindle, an eyelet setting tool carried by the

spindle, said tool having relatively movable parts, one of said parts being rigidly secured to said spindle and adapted to rotate therewith, the other of said parts being provided with a shoulder, a bracket on the column extending towards the spindle, a locking member pivotally mounted on said bracket and having an arm at one end thereof formed with an element for engaging said shoulder to lock said part provided with the shoulder against rotation and thereby condition said relatively movable parts for relative movement therebetween and having an arm at its other end engageable for positioning said locking member, a latch pivotally mounted on said bracket and having a latching arm at one end thereof for engaging said engageable arm of said locking member and having an arm at its other end for operating said latch, and a member carried by said spindle having a finger for engaging the operating arm of said latch to operate the same to release said locking member and permit said element thereof to engage said shoulder upon movement of said spindle towards said bracket and having a second finger for engaging the engageable arm of said locking member to permit movement of said latching arm into latching position relative to said engageable arm and cause said element of said locking member to release said shoulder upon movement of said spindle away from said bracket.

4. In combination with a drill press or the like having a supporting column and a rotatable spindle, an eyelet setting tool carried by the spindle, said tool having relatively movable parts, one of said parts being rigidly secured to said spindle and adapted to rotate therewith, the other of said parts being provided with a shoulder, a bracket on the column extending towards the spindle, a locking member pivotally mounted on said bracket and having an arm at one end thereof formed with an element for engaging said shoulder to lock said part provided with the shoulder against rotation and thereby condition said relatively movable parts for relative movement therebetween and having an arm at its other end engageable for positioning said locking member, a latch pivotally mounted on said bracket and having a latching arm at one end thereof for engaging said engageable arm of said locking member and having an arm at its other end for operating said latch, and a member carried by said spindle having a finger for engaging the operating arm of said latch to operate the same to release said locking member and permit said element thereof to engage said shoulder upon movement of said spindle towards said bracket and having a second finger for engaging the engageable arm of said locking member to permit movement of said latching arm into latching position relative to said engageable arm and cause said element of said locking member to release said shoulder upon movement of said spindle away from said bracket, and resilient means for urging said locking member into shoulder engaging position.

5. In combination with a drill press or the like having a supporting column and a rotatable spindle, an eyelet setting tool carried by the spindle, said tool having relatively movable parts, one of said parts being rigidly secured to said spindle and adapted to rotate therewith, the other of said parts being provided with a shoulder, a bracket on the column extending towards the spindle, a locking member pivotally mounted on said bracket and having an arm at one

end thereof formed with an element for engaging said shoulder to lock said part provided with the shoulder against rotation and thereby condition said relatively movable parts for relative movement therebetween and having an arm at its other end engageable for positioning said locking member, a latch pivotally mounted on said bracket and having a latching arm at one end thereof for engaging said engageable arm of said locking member and having an arm at its other end for operating said latch, a member carried by said spindle having a finger for engaging the operating arm of said latch to operate the same to release said locking member and permit said element thereof to engage said shoulder upon movement of said spindle towards said bracket and having a second finger for engaging the engageable arm of said locking member to permit movement of said latching arm into latching position relative to said engageable arm and cause said element of said locking member to release said shoulder upon movement of said spindle away from said bracket, and resilient means for urging said latching arm into engagement with said engageable arm.

6. In combination with a drill press or the like having a supporting column and a rotatable spindle, an eyelet setting tool carried by the spindle, said tool having relatively movable parts, one of said parts being rigidly secured to said spindle and adapted to rotate therewith, the other of said parts being provided with a shoulder, a bracket on the column extending towards the spindle, a locking member pivotally mounted on said bracket and having an arm at one end thereof formed with an element for engaging said shoulder to lock said part provided with the shoulder against rotation and thereby condition said relatively movable parts for relative movement therebetween and having an arm at its other end engageable for positioning said locking member, a latch pivotally mounted on said bracket and having a latching arm at one end thereof for engaging said engageable arm of said locking member and having an arm at its other end for operating said latch, a member carried by said spindle having a finger for engaging the operating arm of said latch to operate the same to release said locking member and permit said element thereof to engage said shoulder upon movement of said spindle towards said bracket and having a second finger for engaging the engageable arm of said locking member to permit movement of said latching arm into latching position relative to said engageable arm and cause said element of said locking member to release said shoulder upon movement of said spindle away from said bracket, and a spring having one end connected to said locking member and having its other end connected to said latch for urging said locking member into shoulder engaging position upon release of said latch and for urging said latch into latching position upon movement of said locking member out of shoulder engaging position.

7. A tool operating attachment for use in connection with a drill press having a supporting column and a rotatable spindle, comprising a bracket attached to the column, a member pivotally mounted on said bracket adjacent the free end thereof having a locking projection at one end and an arm at its other end, a latch pivotally mounted on said bracket adjacent said member having a latching arm at one end for engaging the arm of said member and having an

operating arm at its other end, and an operating member attached to the spindle having an element for engaging the operating arm of said latch to effect unlatching of said pivotally mounted member and having a second element for engaging the arm of said pivotally mounted member to move the same out of locking position and into position so as to permit said latching arm to be moved into latching position.

8. A tool operating attachment for use in connection with a drill press having a supporting column and a rotatable spindle, comprising a bracket attached to the column, a member pivotally mounted on said bracket adjacent the free end thereof having a locking projection at one end and an arm at its other end, a latch pivotally mounted on said bracket adjacent said member having a latching arm at one end for engaging the arm of said member and having an operating arm at its other end, an operating member attached to the spindle having an element for engaging the operating arm of said latch to effect unlatching of said pivotally mounted member and having a second element for engaging the arm of said pivotally mounted member to move the same out of locking position and into position so as to permit said latching arm to be moved into latching position, and a spring for effecting movement of said pivotally mounted member upon unlatching thereof.

9. A tool operating attachment for use in connection with a drill press having a supporting column and a rotatable spindle, comprising a bracket attached to the column, a member pivotally mounted on said bracket adjacent the free end thereof having a locking projection at one end and an arm at its other end, a latch pivotally mounted on said bracket adjacent said member having a latching arm at one end for engaging the arm of said member and having an operating arm at its other end, an operating member attached to the spindle having an element for engaging the operating arm of said latch to effect unlatching of said pivotally mounted member and having a second element for engaging the arm of said pivotally mounted member to move the same out of locking position and into position so as to permit said latching arm to be moved into latching position, and a spring for retaining said latch in latched position.

10. A tool operating attachment for use in connection with a drill press having a supporting column and a rotatable spindle, comprising a bracket attached to the column, a member pivotally mounted on said bracket adjacent the free end thereof having a locking projection at one end and an arm at its other end, a latch pivotally mounted on said bracket adjacent said member having a latching arm at one end for engaging the arm of said member and having an operating arm at its other end, an operating member attached to the spindle having an element for engaging the operating arm of said latch to effect unlatching of said pivotally mounted member and having a second element for engaging the arm of said pivotally mounted member to move the same out of locking position and into position so as to permit said latching arm to be moved into latching position, and a spring having one end connected to said pivotally mounted member and having its other end connected to said latch for retaining said latch in latching position and for effecting movement

of said pivotally mounted member upon unlatching thereof.

11. An eyelet setting tool comprising a rotatable casing, a rotatable eyelet setting member mounted for relative axial movement in said casing, a rotatable member rigidly connected to said setting member, means on said casing adapted to be arrested to prevent rotation of said casing, and means operated by said rotatable member for rapidly vibrating said casing axially with respect to said eyelet setting member.

12. An eyelet setting tool comprising a rotatable casing, a rotatable eyelet setting member mounted for relative axial movement in said casing, a rotatable member rigidly connected with said setting member, and means operated by said rotatable member for rapidly vibrating said casing axially with respect to said eyelet setting member, said casing and rotatable member being constructed and arranged for relative rotation therebetween and said casing having a projection thereon adapted to be engaged to prevent rotation of said casing and thereby condition said aforementioned elements for rotation of said rotatable member with respect to said casing.

13. An eyelet setting tool comprising a rotatable casing, a rotatable eyelet setting member mounted for relative axial movement in said casing, a spring for urging said casing in one direction with respect to said member, a rotatable member rigidly connected with said setting member, means on said casing adapted to be arrested to prevent rotation of said casing, and means operated by said rotatable member cooperating with said spring for rapidly vibrating said casing axially with respect to said eyelet setting member.

14. An eyelet setting tool comprising a tubular casing having a constricted tubular lower end for engagement with a work piece and having a longitudinally extending slot in the side wall thereof, a rotatable spindle coupled to said casing for relative rotation with respect thereto, an eyelet spinning member carried by said spindle for rotation therewith and extending to the lower end of said casing for engaging an eyelet associated with the work piece, a cam element on said spindle arranged for rotation therewith, a second cam element disposed in cooperating relation with said first cam element and having

a lateral projection extending into said slot to lock the same against rotative movement with respect to said member and permit axial movement thereof with respect to said casing, and a spring in said casing supported at one end by said casing and having its other end engaging said second cam element to urge the same into engagement with said first cam element.

15. An eyelet setting tool comprising a tubular casing having a constricted tubular lower end for engagement with a work piece and having a longitudinally extending slot in the side wall thereof, a rotatable spindle coupled to said casing for relative rotation with respect thereto, an eyelet spinning member carried by said spindle for rotation therewith and extending to the lower end of said casing for engaging an eyelet associated with the work piece, a cam element on said spindle arranged for rotation therewith, a second cam element disposed in cooperating relation with said first cam element and having a lateral projection extending into said slot to lock the same against rotative movement with respect to said member and permit axial movement thereof with respect to said casing, and a spring in said casing supported at one end by said casing and having its other end engaging said second cam element to urge the same into engagement with said first cam element, said casing having a lateral projection thereon adapted to be engaged to prevent rotative movement of said casing with respect to said spindle and thereby condition said casing and spindle for relative rotation therebetween.
